UNITED STATES PATENT OFFICE.

THOMAS ELLIOTT, OF CINCINNATI, OHIO, ASSIGNEE TO THE CINCINNATI CAR COMPANY, OF CINCINNATI, OHIO, A CORPORATION OF OHIO.

RAILWAY-CAR WINDOW.

Application filed October 20, 1924. Serial No. 744,688.

To all whom it may concern:

Be it known that I, THOMAS ELLIOTT, a citizen of the United States, residing at Cincinnati, in the county of Hamilton and State of Ohio, have invented certain new and useful Improvements in Railway-Car Windows, of which the following is a specification, reference being had therein to the accompanying drawing.

10 This invention relates to improvements in railway car windows, and more particularly to a sash-raising mechanism, and window guards combined with a sash.

The object of the invention is to provide a rack and pinion mechanism for raising, lowering, and holding in any adjusted position the window sash of a car and to combine therewith guard rods or bars which are connected to and travel with the sash and occupy the window space that the sash would otherwise leave open when up or partly up. In this way passengers, and particularly children, are prevented from leaning out of the window opening and are protected from any danger of falling out of the window when the sash is up; while by means of my improved mechanism the guard rods or bars as well as the sash are held in any position to which the sash may be adjusted, the friction between the several operating gears and rack bar being sufficient to hold the sash and its attached guards in any adjusted position.

In the accompanying drawings forming a part of this specification:

Figure 1 is a transverse sectional view through one side of a railway car showing my improved sash mechanism, the view being taken on the line 1—1 of Figure 2 looking in the direction of the arrow.

Figure 2 is an interior view of part of the side of a car, looking from the interior of the car outward and with the inner side plate removed and the sash mechanism partly in section and partly in elevation.

My invention is applicable to any of the usual types of railway cars, more particularly city and interurban cars.

In the drawings the numeral 1 indicates an upper side post, 2 a lower side post, 3 a window sill with a filling 4, a skirt or trim 5 and a stool 6. Between each two upper posts 1 are mounted to slide up and down in the usual way the usual sash one of which is

indicated at 7. Such sash is adapted to be raised and lowered so as to open or close the window opening. To the sash I connect my operating mechanism and my guard bars or rods. To this end I attach to the lower sash rail an angle plate 8 which for purposes of giving a finish I overlay with a molding 9, recessed at intervals on its under side to accommodate the heads of the guard rods and the upper end of the rack bar. These guard rods are indicated at 10 and are connected to the plate 8 as by having their ends upset in addition to tightly fitting holes in the plate. The rods extend down into a space or pocket 11, see Figure 1, formed between the outer plate 12 and inner plate 13 of the car side.

To encase or guide these rods I provide guide tubes 14 secured to guide collars 15 which are fitted tightly in the stool of the window opening. The tubes extend down through the pocket 11 and are held near their lower ends by bushing 16 which have threaded extensions on which are screwed nuts 17 to bind their heads 18 against a plate 19 which forms a part of the interior car construction in making up the side pocket. In this way the guard rods 10 are guided and made readily slideable no matter what their position of up or down adjustment may be. When the sash is wholly or partly up these guard rods extend across the sash openings from the window stool to the lower sash bar, and thus constitute guards which prevent passengers from leaning out of the window openings and exposing themselves to danger. The rods also prevent children from liability to fall out of the window openings when the sashes are up. Thus these guard rods perform a very useful purpose.

I will now refer to the means for operating the sash, either to raise or lower it and to hold it in any adjusted position. These means comprise a rack bar 20 secured to the angle plate 8 through the use of collar 21 attached to the plate and within which the rack is firmly secured. The rack is positioned about midway the width of the sash so as to lift equally both sides of the sash. The rack extends down into the pocket 11 before referred to. It is guided and held in proper position with relation to the operating gear presently to be mentioned,

by passing through a gear casing 22 and in contact with a guide plate 22^a secured, as by screws, to the casing, as seen in Figure 2.

This casing comprises a cover or face 23

5 adapted to fit on and be secured to the inner side plate 13 of the car body, and having a shell 24 which extends through the side plate and into the pocket 11. This shell has openings 25 through which the rack bar passes. Bearings 26 and 27 are formed in this gear casing to support the shafts of the pinions 28 and 29 respectively. The pinion 29 has mounted on its shaft a crank or handle 30 by which it may be rotated. The pinion 28 meshes with the teeth of the rack bar 20 and thereby operates it and the sash up and down. On the shaft of this pinion 28 is mounted an intermediate gear 31 which meshes with the pinion 29 and is thereby 15 rotated so as to revolve the pinion 28 and in turn reciprocate the rack bar 20 to elevate and lower the window sash.

As the inner plate 13 of the car body is usually quite thin, it is desirable to reinforce this plate at the place where this gear casing generally designated 21 is located. To this end I provide a reinforcing plate 32 which is secured preferably at its four corners to the car plate as by screws 33. This reinforcing plate and these fastening screws are indicated in dotted lines in Figure 2 because in that figure the inner side plate of the car has been broken off to expose the sash operating mechanism.

35 It is found to be unnecessary to equip the sash or this operating mechanism with any means for locking them in any adjusted position because the friction between the gearing, and between them and the rack bar, 40 and the friction between the rack bar and the guide rods and their guides is found to be sufficient to cause the sash to remain in any adjusted position. And this is particularly so in cases where, as is almost universal, the sashes are equipped with the usual anti-rattling or friction springs.

45 It will further be observed that this sash-raising mechanism does not require that the sill 3, the outer portion of which fits against the side plate of the car and constitutes in effect a belt rail, shall involve weakening such sill or rail. Small holes merely are needed for the passage of the rods 10 and 20. So that I have preserved or not interfered with the strength and rigidity of the sill or guard rail and at the same time provided this efficient sash raising and lowering mechanism.

50 It will now be seen that my invention affords a readily applied mechanism or window equipment by which the several functions of raising and lowering the sashes, maintaining them in any adjusted position, and safe-guarding passengers, are performed.

I desire to comprehend within my invention such modifications and changes as may be necessary to adapt it to varying conditions.

Having thus fully described my invention, 70 what I claim as new and desire to secure by Letters Patent of the United States, is:

1. The combination with a railway car having a window opening and a sash mounted therein, of guard rods secured to the 75 sash and adapted to move therewith, and operating mechanism to adjust the sash and its guard rods to different positions, comprising a rack bar carried by one of said guard rods, a crank and intermediate gear 80 by which the rack is operated through the crank, such mechanism being mounted on the side of the car beneath the window sill.

2. The combination with a railway car 85 having a window opening and a pocket in its side beneath such opening, of a sash slidably mounted in the opening, a series of guard rods depending from the sash and adapted to extend across the window opening when the sash is raised and to recede 90 into the pocket when the sash is lowered, and operating mechanism comprising a rack carried by one of said guard rails, a pinion meshing with the rack, another pinion and 95 a crank therefor, and an intermediate gear by which the latter pinion rotates the former, said gears being located within a pocket 100 in the side of the car below the sill and such crank being located outside of the pocket but within the car and below the sill.

3. The combination with a car having a window opening and a pocket beneath the opening, of a sash slidably mounted in the opening, guard rods secured to the sash, guide tubes secured in the pocket and adapted to receive the guard rods, a rack bar secured to the sash and extended into the pocket, a gear casing secured to the inner wall of the pocket, pinions mounted in bearings in said casing, one pinion meshing with the rack bar and the other having a crank 105 to operate it, and an intermediate gear meshing with the crank pinion and connected with the rack pinion, such casing, 110 gears and crank being located below the window sill.

4. The combination with a car having a 120 window opening and a pocket in its side beneath the opening, of a sash, an angle plate secured to the sash, a molding covering the plate, a series of guard rods connected to the plate, a like series of guide tubes secured within the pocket and adapted 125 each to receive a rod, a rack bar also secured to the plate and extended into the pocket, a gear casing secured to the inner wall of the pocket and having a shell projecting within the pocket, with openings for the 130

— rack bar and bearings for pinions, a pinion in one set of bearings meshing with the bar, another pinion in another set of bearings and having a crank, and an intermediate gear meshing with the crank pinion and connected with the rack pinion, the relation of the parts being such as to develop friction to maintain the parts with the sash in adjusted positions, such pocket gearing and crank being located below the window sill.

5. The combination with a railway car having a window opening and a sash mounted therein, of guard rods secured to the

sash and adapted to move therewith, and operating mechanism to adjust the sash and 15 its guard rods to different positions, and a sill plate through which the guard rods pass, the sill extending downward against the outside of the side plate of the body and constituting a belt rail element, such 20 operating mechanism being located beneath such sill and within a pocket formed in the side of the car body.

In testimony whereof, I affix my signature.

THOMAS ELLIOTT.
